UNITED STATES PATENT OFFICE.

ALFRED INSINGER, OF PHILADELPHIA, PENNSYLVANIA.

BASKET FOR HOLDING DISHES AND PLATES.

No. 928,762.

Specification of Letters Patent.

Patented July 20, 1909.

Application filed March 10, 1908. Serial No. 420,851.

To all whom it may concern:

Be it known that I, ALFRED INSINGER, a citizen of the United States, residing at Philadelphia, in the county of Philadelphia and State of Pennsylvania, have invented a certain new and useful Improvement in Baskets for Holding Dishes or Plates, of which the following is a specification.

This invention relates to baskets for holding dishes or plates while they are being cleansed by washing machines, and it has for object to provide a simple, durable and inexpensive basket adapted to hold the dishes or plates firmly while in process of 10 cleansing and rinsing, and it consists of the parts and combinations of parts hereinafter described and claimed.

In the accompanying drawings, forming a part of this specification, Figure 1 is a perspective view of my improved dish holding basket. Fig. 2 is a longitudinal vertical section through the basket. Fig. 3 is a transverse vertical section through the basket.

Similar letters refer to similar parts throughout the several views.

Referring to the drawings A represents the top bar and B the bottom bar of the ends and sides of the basket. The bars named are 30 arranged at a suitable distance apart and are bent to shape and to form the sides and ends of the basket. The bottom, proper, of the basket is composed of the bars C, D, and E, extending lengthwise of the basket and having their ends bent upwardly and riveted to the top and bottom bars A and B, the ends of the bars C and D terminating in line with the top bar A and the bars E extending past said top bar and being connected by a bar F in order to form handles for the basket.

Near one end of the basket a bar G is arranged across the basket and its ends bent at right angles, as at a, and riveted to the top bar. The bar G thus serves as a brace or stay for the basket and one of its ends, and serves as a splice bar, to connect the abutting ends of the top bar A.

The transverse bar G is bent at its center, 50 as at c, toward the adjacent end of the basket, and supports one side of a wire netting H which is secured thereto by a loop d. The wire netting is shaped to form a pocket or compartment at one end of the basket, and it is also secured by a wire loop to one

of the upright bars at the end of the basket. At the other end of the basket a bar I is arranged across the basket and has its ends bent at right angles and riveted to the top bar. This bar, I, is bent at its center away from the adjacent end of the basket, as at e, and serves as a support for a wire netting J which is bent to shape and fits in the end of the basket in order to form a pocket therein. The netting J is secured to the bar I by a wire 65 loop f and to the bent end of one of the bottom bars, as at g.

To the inner face of the top bar A at each side of the basket a narrow metal plate K having a series of lugs h projecting at right angles therefrom, is secured, said lugs being preferably triangular in shape.

To the bars E plates L having lugs i, similar to those above described, are riveted in the space between the pockets formed by the 70 wire nettings H and J which lugs, as best shown in Fig. 2, alternate or break joint with the lugs on the top bar.

N represents a cylindrical bar which extends longitudinally of the basket and is arranged a short distance above the bottom thereof and has its ends secured in the central end bar D at each end of the basket. The bar N serves as a stay for the basket and also as a rest or support for the dishes the 85 edges of which rest against each side thereof, as shown in dotted lines, Fig. 1.

In using the basket the dishes or plates are arranged upright with their edges between the lugs i at the bottom and the lugs h at the top of the basket and their backs toward or facing the bar G, so that the dishes or plates stand obliquely in the basket and rest against the bar N. This arrangement of the dishes or plates provides for the access of water to 90 all parts of the dishes or plates when the basket is lowered into the tanks and at the same time insures the dishes or plates being firmly held against movement while the basket is being lowered and raised in the 100 washing and rinsing tanks.

The basket is composed wholly of galvanized metal to insure durability and prevent the same rusting.

The purpose of the pockets formed by the 105 wire nettings H and J is to receive articles of table ware such as knives, forks, and spoons, and in which they are loosely thrown and from which they cannot escape while being cleansed.

Having thus described my invention what I claim as new and desire to secure by Letters Patent is:

1. A basket for holding dishes or the like having bars disposed at the top of the opposite sides of the basket provided with spaced lugs, a pair of bars disposed upon the bottom of the basket and provided with similarly spaced lugs, and a rod connecting the ends of the basket between the top and bottom thereof and located approximately midway the bars on the bottom of the basket.

2. A basket for holding dishes or the like, comprising a rectangular frame provided with side and bottom bars, bars at each end extending across the top of said frame, said bars being disposed at an angle to the side bars and having the opposite halves thereof disposed at an angle to each other, each half 20 of one bar being parallel with the corresponding half of the other bar, bars having spaced lugs secured to the top of the frame between said angularly disposed bars, a rod connecting the ends of the frame between the top and bottom thereof and in line with the centers of said angularly disposed bars, and bars provided with spaced lugs secured to the

bottom of the frame between said angular bars and upon the opposite sides of said rod.

3. A basket for holding dishes or the like, comprising a rectangular frame provided with side and bottom bars, bars at each end extending across the top of said frame, said bars being disposed at an angle to the side bars and having the opposite halves thereof disposed at an angle to each other, each half 35 of one bar being parallel with the corresponding half of the other bar, bars having spaced lugs secured to the top of the frame between said angularly disposed bars, a rod connecting the ends of the frame between the top and bottom thereof and in line with the centers of said angularly disposed bars, bars provided with spaced lugs secured to the bottom of the frame between said angular bars 40 and upon the opposite sides of said rod, and a foraminous pocket at each end of said frame.

In testimony whereof, I affix my signature, in the presence of two witnesses.

ALFRED INSINGER.
